CLAIM

The ornamental design for a cooking pan, as shown and described.

DESCRIPTION

FIG. 1 is a top, front, right-side, perspective view of a cooking pan;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a top, front, right-side, perspective view of an alternate embodiment with a lid shown in broken line as additional unclaimed matter.

In the drawings, the broken lines are for the purposes of illustrating environment and portions of the cooking pan, none of which are part of the claimed design.

1 Claim, 6 Drawing Sheets(56)
